(57) **CLAIM**

The ornamental design of a land clearing tool assembly with a depth control ring and a drum interface, as shown and described.

DESCRIPTION

FIG. 1 is a left isometric view of a land clearing tool assembly with a depth control ring and drum interface showing our new design in assembled condition;

FIG. 2 is a close-up view of the claimed subject matter in FIG. 1

FIG. 3 is a left rear isometric view thereof;

FIG. 4 is a close-up view of the claimed subject matter in FIG. 3;

FIG. 5 is a left side view thereof;

FIG. 6 is a right side view thereof;

FIG. 7 is a front view thereof;

FIG. 8 is a close-up view of the claimed subject matter in FIG. 7;

FIG. 9 is a rear view thereof;

FIG. 10 is a close-up view of the claimed subject matter in FIG. 9;

FIG. 11 is a top view thereof;

FIG. 12 is a close-up view of the claimed subject matter in FIG. 11;

FIG. 13 is a bottom view thereof;

FIG. 14 is a close-up view of the claimed subject matter in FIG. 13;

FIG. 15 is an enlarged left isometric view of a land clearing tool assembly with a depth control ring and drum interface shown isolated from the drum interface of FIG. 1;

FIG. 16 is a left rear isometric view thereof;

FIG. 17 is a left side view thereof;

FIG. 18 is a right side view thereof;

FIG. 19 is a front view thereof;

FIG. 20 is a rear view thereof;

FIG. 21 is a top view thereof; and,

FIG. 22 is a bottom view thereof.

The broken line showing of the tool assembly in FIGS. 1-14, and the broken lines on the surface of the claim in FIGS. 1-22 is included for the purpose of illustrating environmental structure and forms no part of the claimed design.
